DES. 2434

Letters Patent No. 2434, Take out Sept. 25, 1866.

Design for Cancelling Stamp.

To all whom it may concern,

Be it known that I, B. B. Hill of Springfield, County of Hampden and State of Massachusetts, have invented and produced a new and original pattern or Design for a Brand or Cancelling Stamp; and I do hereby declare that the following is a full and exact description of the same or reference being had to accompanying illustrations and lettered parts thereto.

In the accompanying drawings are shown a photograph of a piece of this stamp. a, is the stock. b, is a head plate. c, are ribbon cases. d, is the impression wheel case. e, is the day of the month dial. f, is the month dial. g, is a depression. h, is an impression block or plate. i, is a type long hole combined, or arranged to produce a new and rich Design for a Brand Cancelling Stamp.

What I claim is the said design to be my Letters Patent is the Design for a Cancelling Stamp substantially as illustrated and described.

Witness,

B. B. Hill
